SIGNALING SYSTEM

Gilbert S. Vernam, Hackensack, N. J., and Ronald S. Wishart, Rockville Centre, N. Y., assignors to Postal Telegraph-Cable Company (New York), New York, N. Y., a corporation of New York

Application July 10, 1935, Serial No. 30,630

7 Claims. (Cl. 177—367)

This invention relates to new and useful improvements in signaling systems, and more particularly to call circuit registering and testing arrangements.

5 The main object of the present invention is to provide a switching arrangement at a central office whereby, if faults develop on call circuits terminating at the office, the nature of the fault may be determined and the continued operation 10 of the system insured by the simple expedient of sequentially operating a switching device through a plurality of predetermined positions.

The switching device may, in accordance with one embodiment of the invention, consist of two 15 keys. By operating one key or the other, or both keys together, the circuits at the office may be readjusted to compensate for all abnormal loop conditions.

In accordance with another embodiment of 20 the invention, a rotary switch is provided at the office. The switch is moved step by step from one position to another to provide the required rearrangement of the circuits should a fault develop on a loop.

25 Another object of the invention is to provide a switching arrangement for associating testing equipment with any one of a plurality of loop circuits. The switching may be performed by the alternate actuation of contacts provided 30 on two keys, or by means of a rotary switch which successively connects the testing equipment with any one of the conductors of a plurality of loops connected with the office.

These and other objects of the invention will 35 more fully appear from the following detailed description of embodiments thereof and the appended claims.

In the drawings, Figs. 1 and 2 represent diagrammatically signaling systems in which the 40 switching is controlled, respectively, by means of keys, and by means of rotary switches;

Figs. 3 and 3a are, respectively, a plan view and a vertical cross-section of a rotary switch;

Fig. 4 is the circuit diagram of a main office 45 which may be connected with the system shown in Fig. 2;

Fig. 5 diagrammatically illustrates a modification of the test equipment switching device illustrated in Fig. 2; and

50 Figs. 6 and 7 are, respectively, front and side elevations of an assembly of the switching devices diagrammatically indicated in Fig. 2.

Referring to Fig. 1, a plurality of call boxes 1^a and 1^b are associated with the incoming conductor 1, and a plurality of call boxes 2^a and 2^b

are associated with the outgoing line 2 of a line circuit loop. Fifty or more boxes may be connected in series with a loop, and there is no distinction between the boxes until a fault occurs which in effect, divides the loop into two separate lines, some of the call boxes being in the outgoing and the others in the incoming side of the fault. Conductor 1 is connected through normally closed contacts 9 and 4 of key T, the winding of relay A, contact 4 of key O, and contact 7 of key G to ground. The line 2 is connected over contacts 8 and 3 of key T, the winding of relay B, and a resistance 3 to grounded battery. As well known, each call box has two code wheels (see box 1b), one for grounding the line and the other for opening it. The line is first grounded and then interrupted for each signal impulse transmitted. Normally, the line circuit loop is closed over the various call boxes and both relays A and B are energized and maintain their 20 armature attracted. When the line is grounded relay A becomes deenergized and it will remain deenergized when the line is opened. Relay B remains energized when the line is grounded at a call box, but becomes deenergized when the 25 line is opened.

Upon its deenergization, relay A closes a circuit from ground, through the windings of register and bell magnets 5 and 6 in series, and a signal lamp 7 in parallel, the armature and back 30 contact of relay A, contact 2 of key O, and resistance 8 to grounded battery, operating the register, the bell and the signal lamp in the usual manner. Similarly, when relay B becomes deenergized, it closes a circuit from grounded bat- 35 tery 4, through resistance 8, contact 2 of key O, the back contact and armature of relay B, and contact 3 of key O, to operate magnets 5 and 6 and the lamp 7.

During normal operating conditions, the register 5, the bell 6 and lamp 7 are intermittently 40 operated audibly and visually to indicate and record the designation of the box from which a call is sent. Should the line become permanently grounded or open, one or both of the relays A 45 and B would release, permanently lighting lamp 7 and ringing bell 6. To determine the nature of the trouble, the attendant first actuates ground key G and leaves the "open" key O in its normal position. If the lamp 7 still remains lighted, the 50 key O is also actuated. If the lamp remains lighted, key G is restored to normal and key O left actuated.

In response to one of these operations, the lamp 7 becomes extinguished and the condition 55

of the keys G and O indicates the nature of the line trouble; (1) when lamp 7 is out with both keys normal, the line is normal; (2) with key G operated and O normal, the lamp goes out if the line is grounded; (3) with G normal and O operated, the lamp goes out if the line is open; and (4) with both keys actuated, if one or the other side of the line is grounded, and the other open, the lamp goes out.

10 The circuits in case (1) have already been traced. In case (2), relay B is held energized by the permanent ground on the loop, since its winding is connected direct to grounded battery over resistance 3. Relay A is energized over key contacts O₄ and G₁. Interruptions of either loop conductor will be repeated by one of the relays.

15 In case (3), both relays become deenergized upon the opening of the line, but with key G normal and O actuated, the lamp circuit is interrupted in contacts 2 and 3 of key O. Ground impulses applied to either conductor of the loop will operate one of the relays and the call will be recorded in the usual manner.

20 In case (4), the lamp circuit will be prepared through the armatures and front or back contacts of relays A and B, contacts G₅ and O₁, and resistance 8 to grounded battery. This circuit will, of course, be closed only when one of the relays is operated from a call box.

25 30 The operation of either key or both keys will, in contacts G₁ and 2 and O₄ and 5, switch relay A from ground to grounded battery, whereby under all line conditions register 5 can be controlled from a call box.

35 40 45 In case (4), since grounded battery is connected through resistance 8, key contacts O₁ and G₅ to the armature of relay B, open circuit impulses from call boxes on the grounded line section will release the relay that happens to be energized, connecting register 5 to the battery over the back contacts of relays A and B in series. Ground impulses from boxes on the open side of the loop will operate B or A (whichever happens to be released) to close the register circuit through the front contacts of the two relays in series.

50 It will be seen, therefore, that the register will operate regardless of the side of the loop which is open or grounded and it is not necessary to have separate switch settings for the "grounded and open" and the "open and grounded" conditions as is the case with usual call circuit arrangements.

55 60 65 When it is desired to switch line 1, 2 to another office (e. g., for night service), the right-hand contacts of key T are actuated and the line extended over contacts 7 and 10. By actuating the left-hand contacts of key T, the loop is connected with a test circuit common to a plurality of call circuits 1 and 2, 1', 2', etc. Only one key T, T', etc., should be moved into the testing position at a time.

70 In the test circuit, the line 1 extended through contacts T₅ is connected to contacts L₆ and 7 and through T₆ and relay A to the normal ground connection, and line 2 over T₁ to L₂ and 3 and through T₂ and the normal circuit to battery 4. If now the left-hand contacts of key L are operated, a circuit is closed from grounded battery 4, through relay B, T₁, L₄, B₂ and 3, milliammeter 9, call box 10, B₇ and 2, L₁, T₂ and 8, to conductor 2 and including milliammeter 9 and call box 10 in the line. The milliammeter 9 indicates the current in the outgoing line 2 and the call box 10 can be used to send signals over

this line in a manner similar to the normal call box operation.

By operating the right-hand contacts of key L, a similar test may be made of the incoming line 1 through the circuit traced above.

When key B is operated in either direction, a tone test relay 11 and a buzzer 12 are substituted in the last traced circuit for meter 9 and box 10 by opening contacts B₂ and B₃ and including relay 11 in series in the line through B₁ and B₄ when B is operated to the left, and by opening contacts B₇ and B₈ and including relay 11 in series in the line through B₆ and B₉ when B is operated to the right. The left-hand contacts of key B, when closed connect the buzzer 12 through the armature and front contact of relay 11, and B₅ to grounded battery. Under the control of relay 11, the buzzer 12 operates to locate open faults. When the right-hand contacts are operated, the buzzer circuit extends through the back contact of relay 11 and B₁₀ for locating grounds.

The lineman tests for open faults by means of a telephone receiver 13 which by means of a clip 14 and a needle point 15 he connects from the line to ground, depressing button 16 to short-circuit a condenser 17 thus completing a closed circuit through relay 11 when the point grounded is on the side of the line away from battery 4. This will operate relay 11 which, in turn, operates buzzer 12, the tone generated being coupled to the line through condenser 18. If the point grounded is on the other side of the open fault the circuit will not be completed through 11 and accordingly no tone will be generated. The tone is heard by the lineman in the receiver 13, whereby he can identify the side of the loop relative to the break on which he is testing.

If the loop is grounded, the test receiver 13 is inserted in series with one or the other side of the loop. In this case key B should be operated to the right inserting relay 11 in series with the line and connecting battery 4 to the back contacts of relay 11. Since relay 11 will have its circuit completed through the grounded point of the line, it will normally be energized. Releasing key 16 will open the line, releasing relay 11 and closing the circuit through the buzzer 12, producing a tone in receiver 13. If the test is made on the side of the grounded point in the line remote from the tone tester, no sound will be heard in the receiver 13.

In the arrangement shown in Fig. 2, a single rotary line switch 50 having five positions is substituted for keys G and O and the right-hand contacts 7-10 of key T of Fig. 1. A rotary test switch 51, common to a group of not more than five loops, is operable to connect the testing equipment to either side of any loop, thus replacing the left-hand contacts 1-5 of key T and contacts 1-8 of key L of the arrangement shown in Fig. 1.

The switches 50 and 51 consist each of three sections, one of which is shown in Figs. 3 and 3a. These sections are mounted on a common shaft 52. Each section has two rotating segments or rotors 53 and 54 of conducting material. The rotor sections are so shaped as to surround shaft 52 but are spaced therefrom. They are held together and mounted on the shaft by means of a disc 55 of insulating material to which the rotor segments are riveted. The disc 55 has a cross-shaped perforation which fits over a section of shaft 52, the cross-section of which is similarly shaped as indicated at 56. Each of the rotor

segments 53, 54 has a projection 50^a and 50^b, respectively, which operate as wipers and are diagrammatically represented in Fig. 2. The wipers cooperate with a circular bank of terminals, 1-5 for each wiper, mounted on a ring of insulating material surrounding shaft 52. A common contact 53^a mounted on ring 57 engages the rotor section 53, and a common contact 54^a also mounted on ring 57 engages rotor segment 54 in all positions of shaft 52. Each section is, therefore, a two-pole five-position switch, and three such sections mounted on a common shaft constitute a six-pole five-position switch. Only five of the six poles are used in the line switch 50. Ring 57 is fastened by means of tubular bushings 58 mounted on screw threaded rods 58^a to a plate 59. The head of screw 58^a is above plate 59 and the screw extends through lower plate 57 into another tubular bushing. Both screw and bushing are shown broken off to indicate that additional contact plates may be added as required. Actually the switch has three plates like 57 and a bottom bearing plate for shaft 52. Corrugations 60 formed in plate 59 are engaged by a ball 61 carried by the free end of a leaf spring 62. The other end of spring 62 is doubled back as indicated at 63 and perforated to fit over section 64 of shaft 52. Section 64 is shaped like section 56 and, when shaft 52 is rotated by means of a handle 65 mounted in front of a panel 66, it carries with it spring 62. The corrugations 60 are so positioned that wipers 53^a and 54^a will be properly centered on a terminal when ball 61 rests in a recess between two corrugations 60. Suitable stops (not shown) are provided to prevent spring 62 and, therefore, the shaft and rotors from rotating beyond the No. 1 or No. 5 positions.

The handle 65 of the line switch 50 is normally in the position marked "normal" on panel 66 (Fig. 6), but when line trouble occurs, indicated by a steady light of signal lamp 80, it is rotated one step at a time to the right until the lamp goes out. The circuit will then receive calls in spite of the trouble and the pointer of switch knob 65 indicates the nature of the trouble. The extreme right position of the switch is used for transferring the loop to another office for night service.

Referring now to the circuit of Fig. 2, in the normal (#1) positions of line switch 50 and test switch 51, the outgoing line 81 is connected over 51^a, 50^d, resistance 82, and a power switch 83 to grounded battery 84. Current flows through the call boxes in series, and then through the incoming line 85, 51^b, 50^e, winding of relay A¹ and 50^a to ground. Relay A¹ is held energized. Battery is also connected through resistance 86 and 50^c to the back contacts of relays A¹ and B¹. The armature of relay B¹ is open at 50^b, but the armature of relay A¹ is connected with the signal lamp 80, register 87 and a low resistance relay 88, the latter controlling buzzer 89. Relay A¹ will release in response to each impulse from any call box and will cause register 87 to record the code signal. Lamp 80 will flash and buzzer 89 will operate.

If the loop 81, 85 becomes grounded, relay A¹ will permanently release its armature and will cause continuous operation of lamp 80, register magnet 87 and buzzer 89. The attendant will now rotate the knob of the line switch shaft. In the second or "ground" position, the lamp 80 is extinguished and the buzzer stops because both relays A¹ and B¹ become energized, ground being

supplied from the line loop, and battery being supplied to A through resistance 90 and wiper 50^a, and to B¹ through resistance 82. The winding of B¹ is now connected with the outgoing line through the #2 terminal of 50^d. Since over 50^c battery is applied only to the back contacts of A¹ and B¹, the register circuit will be open. Relay A¹ will respond to impulses from call boxes on the outgoing and relay B¹ to impulses from the boxes on the incoming side of the ground fault, whereby calls from any box will be properly registered.

Should the loop go open, relay B¹ remains de-energized, relay A¹ becomes deenergized, and lamp 80 lights steadily. When switch 50 is rotated into the second position the lamp remains lighted over a circuit including resistance 86, 53^c, and the back contact and armature of relay A¹ and in parallel over 50^c, back contact and armature of B¹ and 50^b. The attendant now rotates the switch into the #3 or "open" position, whereby battery 84 is transferred through resistance 86 and 50^c from the back to the front contacts of relays A¹ and B¹. The lamp becomes extinguished and relays A¹ and B¹ may be operated by ground impulses from call boxes on their respective sides of the loop, A¹ being supplied with battery through 50^a and B¹ through 82.

If the loop goes open and one side becomes grounded, relay A¹ becomes deenergized as before. When switch 50 is rotated into the second and third positions, one of the relays A¹ or B¹ will operate and the other remains released, depending on which side of the line is open and which side grounded. The circuit of lamp 80 will be closed through the back contact of one of these relays while the switch is in the second position, and through the front contact of the other relay while the switch is in the third position. When, however, the switch is rotated into the fourth position, battery is applied through 86 and 50^c to the armature of relay B¹ which is disconnected from the register circuit in the open #4 terminal of 50^b. The relay contacts are now connected to operate in series as in Fig. 1 when both keys G and O are operated. The lamp is extinguished and ground impulses from call boxes in the open side of the loop will operate one relay, closing the register circuit through the front contacts of both relays in series. Open impulses from boxes in the grounded side of the loop will release the other relay and close the register circuit through the back contacts of both relays in series, so that calls from any box will be properly recorded.

In the fifth position of switch 50, loop 81, 85 is connected through 50^d and 50^e, and conductors 91, 92, to another or the main office. Both relays A¹ and B¹ become deenergized and, since battery is connected to their back contacts through 50^c, lamp 80 will light. This is a warning signal that power switch 83 be opened or that switch 50 be returned to normal. The last mentioned indication is useful when the power switch 83 is closed upon the beginning of the next business day.

If the same kind of call circuit equipment is used at the main office to which the loop is transferred for night service, the arrangement at this office is as shown in Fig. 4. This circuit is the same as the branch office circuit (Fig. 2) except for changes in the wiring of the fifth contacts associated with rotors 100^c, ^d and ^e of switch 100, corresponding to switch 50. At the main office, switch 100 is left in the fifth or

"transfer" position during the day while the circuit is in use at the branch office. When the branch office switch is turned to the "transfer" position, the loop is closed through conductors 91 and 92 to the main office and relay A¹¹ operates, lighting the signal lamp 80¹. The main office attendant should then rotate the switch 100 to its "normal" position, where it will operate during the night period. In case of line trouble, the main office equipment will function as described for the branch office. When the branch office opens in the morning and restores its line switch 50 to "normal" to take over the messenger service, relay A¹¹ at the main office will release and light the lamp 80¹ as in the case of an open line. The main office switch 100 should be rotated then to the "transfer" position, restoring the circuit to its regular daytime condition.

Referring again to Fig. 2, the test switch 51 and its associated equipment are common to two call circuit loops. In its normal or No. 1 position, loop 81, 85 extends through wipers 51^a and 51^b and loop 81^a, 82^a extends through wipers 51^c and 51^d, and the testing equipment is disconnected. When rotated to its No. 2 position, switch 51 opens the outgoing line 81 and connects test call box 93 and jack 94 in series with this line. The test call box may now be used to check the operation of the relays A¹, B¹ and milliammeter 95 may be plugged into the test jack 94 to measure the outgoing line current as described in connection with Fig. 1. The relay may be tested by transmitting signals in the usual manner and properly manipulating the switches at the call station. The test jack 94 may also be used by the lineman for connecting a portable tone test set 96 to the line to aid in locating line trouble in a manner fully set forth in connection with Fig. 1.

Switch 51, when rotated to the third position, closes the outgoing line 81 and connects the testing equipment in series with the incoming line 85. This switch when rotated to positions 4 and 5, connects the testing equipment in a similar manner in series with either side of the second call circuit loop 81^a, 82^a.

Although switch 51, as shown in Fig. 2, is used for testing only four line conductors (or two loops), it is obvious that it could be expanded to handle more circuits by adding rotors and switch contacts. By using a single rotor, formed as a ring with one projecting wiper (see 151^f and ^g of Fig. 5), each section of the switch becomes a single-pole 11-position switch. With 12 such sections, 10 wired like 51^a to 51^d, and two wired like 51^e and 51^f, the switch could be used to test 10 line conductors or both sides of five call circuit loops.

The same result can be accomplished, however, by using only seven sections 151^{a-g}, arranged and wired as shown in Fig. 5, except that the sections are placed along a common shaft instead of being arranged side by side as shown. The first five sections, 151^{a-e}, of switch 150 each have four rotor pieces of special shape and each section is arranged to close two line circuits independently, opening each one of these in only one position of the shaft. For example, it can be seen that circuit #1 is normally closed through contacts of the first switch section 151^a, but will be opened if the switch is rotated one step clockwise as the two short terminal springs 152 and

153 will both be opposite short portions of the rotor. For any other position of the rotor the circuit will be closed because the long center contact spring 153 will be connected to either one or the other of the two short springs 152, 153 through a rotor segment. The same rotor will open circuit 6 when the shaft is rotated six steps from its normal position. The contact springs for the second section 151^b are placed one step (30°) around in a clockwise direction as compared with the first section 151^a, so that circuits 2 and 7 will be opened, respectively, when the switch 151^b is rotated two to seven steps. The contacts for the sections 151^c, 151^d and 151^e are each placed one step further around than those of the preceding section. It is obvious that these five sections will open one circuit at a time in regular order for each rotary step of the switch, all circuits being closed in the extreme left or "normal" position of the switch. Sections 151^f 20 and 151^g serve to connect the test circuit to each of the circuits in succession as they are opened by the other five sections.

This test switch 151 will connect the testing circuit 155 in series with any one of ten line conductors, or either side of any one of five call circuit loop circuits, and is, therefore, equivalent to the usual type of cord and plug and ten line jacks. It is also considerably cheaper than the customary cord and jack arrangement, is more compact and has a better appearance. Where there are more than five loops, a second similar test switch can be connected to the upper right-hand terminals 156. The first test switch must be placed in its normal position to extend the testing circuit to the second switch. A third switch can be connected to the second in a similar manner.

Figs. 6 and 7 show the assembly of a call circuit switchboard for two loop circuits, and illustrate 40 the unit type construction used with the rotary switch type of equipment. The two line units are shown in the upper part of Fig. 6. Each consists of a bent steel bracket 200 held at the bottom by screws 201^a threaded into posts 201 which support the resistance 97. Attached to bracket 200 are the line switch 50 with extended shaft 52, socket 202 for lamp 80, panel 66, terminal strip 203, and insulating block 204 on which are mounted the two relays A, B. One end of the 50 bracket is held by a turned-over portion of the shelf 204^a and the other end is fastened by a screw 205 to a block 206 attached to the same shelf. By removing a single screw 205, the unit can be removed from the shelf 204^a. The lower 55 part of the switchboard consists of a base 207 to which are attached two brackets 208 which support the shelf 204, a terminal strip 209 and a front panel 210. A resistance unit 210 (resistances 82, 86, 90) is mounted on the base 207 60 and the call box 93, test switch 51, power switch 83 and binding posts 211 are mounted on the front panel 210. A test jack 94, as shown in Fig. 2 may be used instead of these binding posts. The assembly is enclosed within a casing 212. 65

The assembly of a larger switchboard for a larger number of loops will be arranged in the same manner as the two-line switchboard. If the board is not completely equipped for, say ten lines, blank panels can be substituted for some 70 of the line units. In this case the test switches, one for each five loops, preferably of the type shown in Fig. 5, are mounted as separate units in a manner similar to the line units. As in the smaller switchboard, the lower part includes the 75

battery tap resistances, line terminal strip and testing equipment. It should be noted that panel 66 is held to bracket 200 by a single screw, so that by attaching switch handle 65 and then removing this screw, the front of the relay is accessible for cleaning contacts or adjusting. The terminals 203 on strip 203a are also accessible for testing. By removing screw 205 and the ten wires from these terminals, the entire line units 10 may be pulled out from the front, with this arrangement, the entire equipment is accessible for maintenance purposes even though a large number of the units are installed in a case mounted against a wall. Standard telephone relay racks 15 may also be used for mounting this equipment in units or shelves of five line relay units and one test switch.

We claim:

1. A signaling system, comprising a line loop having a first and second terminal, a plurality of call boxes each comprising a signal transmitting device for intermittently interrupting the loop and connecting it to ground connected in said loop, a central office at which said loop is terminated and a source of current at said office having one terminal grounded and the other terminal normally connected to said first loop terminal, said other loop terminal being normally grounded, characterized by means for rendering said system operative during abnormal conditions of said line, such as grounding, open circuit or a combination of both conditions, comprising a first and second relay at said office, switch means at said office having a normal and only three other control positions, each of said three other control positions representing a different one of said abnormal conditions on said loop, a circuit for said first relay from ground to said second terminal of the loop closed in the normal position and from said source to said second terminal of said loop closed in the three other positions of said switch means, a circuit for said second relay from said other terminal of said source of current directly over said first loop terminal, separately closed only in said three other positions of said switch means, whereby said second relay is connected with the loop for effecting signal control only in said three other positions but not in the normal position of said switch means, said first relay being operatively connected with said loop for signal control in the normal and three other positions of said switch means, means connecting together the front contacts and the back contacts of said relays, relay armature contact means controlled by said first and second relays, a call register, circuit connections including said first relay contact and armature for controlling said register by operation of said first relay contacts only, in the normal position of said switch means, and other circuit connections including said armatures and contact means of both said relays adjusted by said switch means for controlling said register independently by either of said relays in said three other positions of said switch means. 5. A signaling system, comprising a line loop having a first and second terminal, a plurality of call boxes each comprising a signal transmitting device for interrupting the loop and connecting it to ground connected in said loop, a central office at which said loop is terminated and a source of current at said office having one terminal grounded and the other terminal normally connected to said first loop terminal, characterized by means for rendering said system operative during abnormal conditions of said line, such as grounding, open circuit or a combination of both conditions, comprising a first and second relay at said office, switch means at said office having a normal and only three other control positions, each of said three other control positions representing a different one of said abnormal conditions on said loop, a circuit for said first relay from ground to said second terminal of the loop closed in the normal position and from said source to said second terminal of said loop closed in the three other positions of said switch means, a circuit for said second relay from said other terminal of said source of current directly over said first loop terminal, separately closed only in said three other positions of said switch means, whereby said second relay is connected with the loop for effecting signal control only in said three other positions but not in the normal position of said switch means, said first relay being operatively connected with said loop for signal control in the normal and three other positions of said switch means, means connecting together the front contacts and the back contacts of said relays, relay armature contact means controlled by said first and second relays, a call register, circuit connections including said first relay contact and armature for controlling said register by operation of said first relay contacts only, in the normal position of said switch means, and other circuit connections including said armatures and contact means of both said relays adjusted by said switch means for controlling said register independently by either of said relays in said three other positions of said switch means.
2. A signaling system according to claim 1 wherein said switch means comprises two key controlled switches for establishing said normal and abnormal circuit operation conditions.
3. A signaling system according to claim 1 wherein said switch means comprises a plurality of uni-controlled multi-position rotary switches of substantially similar form for establishing said normal and abnormal system operation conditions.
4. A signaling system, comprising a line loop having a first and second terminal, a plurality of call boxes each comprising a signal trans-

mitting device for interrupting the loop and connecting it to ground connected in said loop, a central office at which said loop is terminated and a source of current at said office having one terminal grounded and the other terminal normally connected to said first loop terminal, characterized by means for rendering said system operative during abnormal conditions of said line, such as grounding, open circuit or a combination of both conditions, comprising a first and second relay at said office each having front and back contacts, switch means at said office having a normal and only three other control positions, each of said three other control positions representing a different one of said abnormal conditions on said loop, a circuit for said first relay from ground to said second terminal of the loop closed in the normal position and from said source to said second terminal of said loop closed in the three other positions of said switch means, a circuit for said second relay from said other terminal of said source of current directly over said first loop terminal, separately closed only in said three other positions of said switch means, whereby said second relay is connected with the loop for effecting signal control only in said three other positions but not in the normal position of said switch means, said first relay being operatively connected with said loop for signal control in the normal and three other positions of said switch means, means connecting together the front contacts and the back contacts of said relays, relay armature contact means controlled by said first and second relays, a call register, circuit connections including said first relay contact and armature for controlling said register by operation of said first relay contacts only, in the normal position of said switch means, and other circuit connections including said armatures and contact means of both said relays adjusted by said switch means for controlling said register independently by either of said relays in said three other positions of said switch means.

5. A signaling system, comprising a line loop having a first and second terminal, a plurality of call boxes each comprising a signal transmitting device for interrupting the loop and connecting it to ground connected in said loop, a central office at which said loop is terminated and a source of current at said office having one terminal grounded and the other terminal normally connected to said first loop terminal, characterized by means for rendering said system operative during abnormal conditions of said line, such as grounding, open circuit or a combination of both conditions, comprising a first and second relay at said office, switch means at said office having a normal and only three other control positions, each of said three other control positions representing a different one of said abnormal conditions on said loop, a circuit for said first relay from ground to said second terminal of the loop closed in the normal position and from said source to said second terminal of said loop closed in the three other positions of said switch means, a circuit for said second relay from said other terminal of said source of current directly over said first loop terminal, separately closed only in said three other positions of said switch means, whereby said second relay is connected with the loop for effecting signal control only in said three other positions but not in the normal position of said switch means, said first relay being operatively connected with said loop for response to signals in the normal and three other positions of said

switch means, front contacts for said relays connected together and back contacts for said relays connected together, relay armature contact means controlled by said first and second relays, 5 a call register, a signal means normally controlled by said first relay only, and actuated upon occurrence any of said abnormal conditions in said loop connected in parallel with said register, circuits including said contacts and armatures controlled by said relays for releasing said signal means upon operation of said switch means to a position corresponding to the abnormal condition of said loop, and circuit connections including 10 said armatures and contacts controlled by said switch means for controlling said register, by said first relay only in the normal position of said switch means, and independently by either of said relays in said three positions of said switch means.

20 6. A signaling system, comprising a line loop having a first and second terminal, a plurality of call boxes each comprising a signal transmitting device for interrupting the loop and connecting it to ground connected in said loop, a central office at which said loop is terminated and a source of current at said office having one terminal grounded and the other terminal normally connected to said first loop terminal, characterized by means for rendering said system operative during the abnormal conditions of said line, such as grounding, open circuit or a combination of both conditions, comprising a first and second relay at said office, a multi-position rotary switch at the office having a normal and three other positions, each intermediate position representing a different abnormal condition on the loop, a circuit for said first relay from ground to said second terminal of the loop closed in the normal position of said switch and from said source to said second terminal closed in the three other positions of said switch, a circuit for said second relay from said source to said first loop terminal closed only in the three other positions of said switch, said first terminal being connected to said source in all positions of the switch, 40 whereby the second relay is operatively connected with said loop only in said other but not said normal position of the switch and the first relay is operatively connected with the loop in the normal and the other positions of the switch, front contacts for said relays connected together and back contacts for said relays connected together, relay armature contacts controlled by said first and said second relays, a register controlled solely by said first relay contacts in said normal position of the switch and by either of said relay contacts in said other positions of said switch, a signal connected in parallel with said register normally controlled solely by the first relay and

actuated upon the occurrence of an abnormal condition on either limb of said loop, circuits including said contacts and armatures controlled by said relays for releasing said signal when the switch is set into an intermediate position corresponding to the abnormal condition of the loop, and connections including said contacts and armatures for controlling said register by either of said relays in said other positions of said switch. 10

7. A signaling system, comprising a line loop having a first and second terminal, a plurality of call boxes each comprising a signal transmitting device for interrupting the loop and connecting it to ground connected in said loop, a central office at which said loop is terminated and a source of current at said office having one terminal grounded and the other terminal normally connected to said first loop terminal, characterized by means for rendering said system operative during abnormal conditions of said line, such as grounding, open circuit or a combination of both conditions, comprising a first and second relay at said office, a first switching key and a second switching key, each key having a first and second switch position, normal switching position comprising said two keys in their first position, and positions for abnormal conditions of said loop comprising either one or both of said keys in said second position dependent upon the nature of said condition, a circuit for said first relay from ground to said second terminal of the loop closed in the normal of said switch position and from said source to said second terminal of said loop closed in the three other positions of said switch means, a circuit for said second relay from said source to said first loop terminal separately closed only in said three other positions of said switch means, whereby said second relay is connected with the loop for effecting signal control only in said three other positions but not in the normal position of said switch means, said first relay being operatively connected with said loop for signal contact in the normal and three other positions of said switch means, front contacts for said relays connected together and back contacts for said relays connected together, relay armature contacts controlled by said first and second relays, a call register, and circuit connections including said contacts and armatures controlled by said switch means for controlling said register, by said first relay only, in the normal position of said switch means, and independently by either of said relays in said three other positions of said switch means. 50
